UNITED STATES PATENT OFFICE

2,473,547

ELECTRON DISCHARGE DEVICE

Robert C. Schmidt, Newton, Mass., assignor to
 Raytheon Manufacturing Company, Newton,
 Mass., a corporation of Delaware

Application September 28, 1945, Serial No. 619,017

4 Claims. (Cl. 250—27.5)

1

My present invention relates to electron-discharge devices, and more particularly to electron-discharge devices of the so-called magnetron type.

While not limited thereto, my present invention is especially suitable for generating low, continuous-wave power, at low voltages, in the microwave region of the electromagnetic spectrum.

Devices of the general character indicated have heretofore required external magnetic means, and have, therefore, been bulky, and costly to manufacture and assemble. Hence, it is among the objects of my present invention to provide a self-contained magnetron which is compact, and whose components are so designed and arranged as to enable the simple and inexpensive assembling thereof.

These and other objects of my present invention, which will become more apparent as the detailed description thereof progresses, are attained, briefly, in the following manner:

In the magnetron of my present invention, a centrally-disposed cathode member is surrounded by a coaxial, cylindrical anode member provided with a plurality of radially-disposed cavity resonators, the annular space intermediate said cathode and anode members constituting an electron path. A pair of opposed, permanent magnets is arranged on opposite sides of said anode member, in coaxial alignment therewith, to establish a magnetic field in a direction transversely of said electron path. The elements described are supported upon a base member, and are enclosed by an envelope, made of magnetic material, which is hermetically sealed to said base member, at least a part of said envelope constituting at least a part of the return path of the magnetic field established by said permanent magnets. Power is extracted from the device by means of a coaxial line, entering the same through said base member, and being coupled to said anode member.

Such a structure is relatively simple to manufacture and assemble; it is self-contained; and it is compact, thereby eliminating the disadvantages of prior art devices hereinbefore referred to.

In the accompanying specification I shall describe, and in the annexed drawings show, an illustrative embodiment of the electron-discharge device of my present invention. It is, however, to be clearly understood that I do not wish to be limited to the details herein shown and described for purposes of illustration only, inasmuch as changes therein may be made without the exercise of invention and within the true spirit and scope of the claims hereto appended.

In said drawings,

Fig. 1 is a longitudinal sectional view taken substantially through the center of an electron-discharge device made in accordance with the principles of my present invention; and

2

Fig. 2 is an enlarged scale transverse sectional view taken along line 2—2 of Fig. 1.

Referring now more in detail to the aforesaid illustrative embodiment of my present invention, with particular reference to the drawings illustrating the same, the numeral 10 designates an octal base on which is mounted an inverted dish-like header 11. Secured to the header 11 is a dish-like adapter 12 from which rises a plurality, here shown as four, of supporting rods 13 made of non-magnetic material, preferably, Monel metal.

Secured to the rods 13, adjacent the top and near the bottom thereof, is a pair of magnet-supporting discs 14 and 15, made of magnetic material, and, respectively, provided at their peripheries with flanges 16 and 17 directed toward each other, and lugs 18 and 19 punched out of the same to present openings 20 and 21 through which the rods 13 may pass, said lugs constituting the means for fastening said discs to said rods.

Depending from the disc 14, and extending upwardly from the disc 15, is a pair of similar, but magnetically opposed permanent magnets 22 and 23, said magnets, preferably, being cylindrical and provided, respectively, with central bores 24 and 25. Secured against the facing, inner ends of the magnets 22 and 23 is a pair of centrally-bored pole pieces 26 and 27, said pole pieces being additionally supported, respectively, by rings 28 and 29 which are fastened to the rods 13, and the inner ends of said pole pieces being separated to provide a concentrated magnetic field in the space therebetween.

An anode-supporting ring 30 is secured to the rods 13 intermediate the pole-supporting rings 28 and 29, said ring 30 having depending therefrom a cylindrical anode block 31, made of highly conductive material, such as copper, and provided with a multiplicity, here shown as twenty-four, of inwardly-directed, radially-disposed anode arms 32, each pair of adjacent anode arms, together with that portion of said anode block lying therebetween, constituting a cavity resonator whose natural resonant frequency is, as is well known, a function of the geometry of the physical elements making up the same. The anode arms 32 project into the magnetic field intermediate the pole pieces 26 and 27.

In order to suppress spurious oscillations, I prefer that alternate and intermediate anode arms 32 be electrically connected, adjacent their inner ends, respectively, by conducting rings 33 and 34 at the upper edges thereof, and by conducting rings 35 and 36 at the lower edges thereof.

Centrally disposed in the space defined by the inner ends of the arms 32, and extending into the central bores of the pole pieces 26 and 27, is a cathode sleeve 37 made, preferably, of nickel, and provided, in a region coextensive with the height 60 of said anode arms, with a highly electron-emis-

sive coating 38, for example, of the well-known alkaline-earth metal oxide type. Said cathode sleeve 37 is supported, preferably, in a pair of mica insulating discs 39 and 40, in turn, secured, by retaining rings 41 and 42, in recesses 43 and 44 formed, respectively, in the pole pieces 26 and 27.

The coating 38 is raised to emission temperature by a heating filament 45 disposed in the cathode sleeve 37, one end of said filament being electrically connected to said sleeve, as at 46, and the other end thereof being connected, as at 47, to a lead-in conductor 48, which has its outer end secured in a base pin 49, and which enters the inner region of the device through a glass seal 50 carried by an eyelet 51 secured in the header 11. The heating filament circuit is completed by a conductor 52, one end of which is electrically connected, as at 53, to the lower end of the cathode sleeve 37, and the other end of which is connected to a lead-in conductor (not shown), similar to the lead-in conductor 48, and entering the device through like means, and terminating, for example, at a base pin 54. From their respective lead-in conductors, the filament 45 and conductor 52 are separately conveyed through the central bore 25 of the magnet 23 by means of insulating tubes 55 and 56.

In order to protect the pole pieces 26 and 27 from cathode sputtering, the cathode sleeve 37 is provided with shields 57 and 58.

The entire inner assembly is enclosed by a cylindrical envelope or can 59, made of magnetic material and hermetically sealed, as at 60, to the adapter 12, the flanges 16 and 17 of the magnet-supporting discs 14 and 15 being secured to said envelope, as at 61 and 62, whereby said envelope serves as a low-reluctance return path for the magnetic flux emanating from the magnets 22 and 23.

The interior of the device is conventionally evacuated through an exhaust tubulation 63.

Low, continuous-wave power, at low voltages, may be extracted from the device by electrically connecting to one of the anode arms 32 a tab 64 made, preferably, of nickel, said tab being secured at the end of an inner conductor 65 of a coaxial transmission line, and said conductor passing out of the device through a glass seal 66 carried by an eyelet 67 affixed to the header 11. The external end of said conductor 65 terminates in a nickel tube 68 disposed in a recessed insulating member 69 which is carried at the outer end of an outer, tubular conductor 70 of the above-mentioned coaxial transmission line, said outer conductor 70 passing through openings 71 and 72 with which the discs 15 and 29 are, respectively, provided, and terminating just above the lower end of the anode block 31.

This completes the description of the aforesaid illustrative embodiment of my present invention. It will be noted from all of the foregoing that I have provided a self-contained and compact electron-discharge device of the magnetron type, which has been found to be admirably suited to the generation of low, continuous-wave power, at low voltages, in the microwave region of the electromagnetic spectrum.

Other objects and advantages of my present invention will readily occur to those skilled in the art to which the same relates.

What is claimed is:

1. An electron-discharge device comprising: a cathode member; an anode member; said cathode and anode members being spaced to present

an electron path therebetween; means within said device establishing a magnetic field in a direction transversely of said electron path; a base member: means, rising from said base member, supporting said cathode and anode members and said field-establishing means; and an envelope, hermetically sealed to said base member, and cooperable therewith to enclose said cathode and anode members and said field-establishing means; a part of said envelope constituting a part of the return path of said magnetic field.

2. An electron-discharge device comprising: a centrally-disposed cathode member; an anode member surrounding said cathode member, and including a plurality of radially-disposed cavity resonators; said cathode and anode members being spaced to present an electron path therebetween; means within said device establishing a magnetic field in a direction transversely of said electron path; a base member; means, rising from said base member, supporting said cathode and anode members and said field-establishing means; and an envelope, hermetically sealed to said base member, and cooperable therewith to enclose said cathode and anode members and said field-establishing means; a part of said envelope constituting a part of the return path of said magnetic field.

3. An electron-discharge device comprising: a centrally-disposed cathode member; an anode member surrounding said cathode member and including a plurality of radially-disposed cavity resonators; said cathode and anode members being spaced to present an electron path therebetween; a pair of spaced, permanent magnets, coaxially aligned with said cathode and anode members, establishing a magnetic field in a direction transversely of said electron path; a base member; means, rising from said base member, supporting said cathode and anode members and said permanent magnets, and an envelope, hermetically sealed to said base member, and cooperable therewith to enclose said cathode and anode members and said permanent magnets; a part of said envelope constituting a part of the return path of said magnetic field.

4. An electron-discharge device comprising: a cathode member; an anode member; said cathode and anode members being spaced to present an electron path therebetween; a pair of opposed magnets establishing a magnetic field in a direction transversely of said electron path; a base member; a plurality of rods extending from said base member; members extending from said rods to support said anode member and said magnets; said cathode member being supported, in turn, by said magnets; and a can, made of magnetic material and hermetically sealed to said base, for enclosing said cathode and anode members and said magnets; a part of said can constituting a part of the return path of said magnetic field.

ROBERT C. SCHMIDT.
